UNITED STATES PATENT OFFICE.

THEODORE S. ETHERIDGE, OF GRAND RAPIDS, MICHIGAN.

DEVICE FOR ATTACHING BOOK-COVERS.

1,114,740.

Specification of Letters Patent. Patented Oct. 27, 1914.

Application filed June 4, 1913. Serial No. 771,746.

To all whom it may concern:

Be it known that I, THEODORE S. ETHERIDGE, a citizen of the United States of America, residing at Grand Rapids, in the 5 county of Kent and State of Michigan, have invented certain new and useful Improvements in Devices for Attaching Book-Covers; and I do hereby declare the following to be a full, clear, and exact description 10 of the invention, such as will enable others skilled in the art to which it appertains to make and use the same.

My invention relates to improvements in devices for attaching book covers, and its 15 object is to provide a device of this character which will hold the book, together with the end sheets, in position to apply the glue thereto, and will also provide a guide for placing the outer cover in position, to provide a device which will be simple in construction and operation, which will be adjustable to accommodate books of various 20 dimensions and to provide the same with certain new and useful features hereinafter 25 more fully described and particularly pointed out in the claims.

It is common practice in the art of book binding, especially when binding paper covered books such as pamphlets, catalogues, 30 etc., on which a double thickness of cover is used, to first attach the inner part of the cover commonly known as the end sheets, to the book after which the glue must be spread upon these end sheets, and also to the back 35 edge of the book in order to affix the cover thereto.

The device consists of means for clamping the book while the above mentioned operation is being performed, and also for supporting the end sheets in outspread position 40 so that the glue may be easily and properly applied thereto.

The device is also provided with means by which the cover may be guided to proper position, and the device is also adapted to be adjusted to accommodate books of various dimensions, and is provided with certain other novel features of construction and arrangement, as will more fully appear by 50 reference to the accompanying drawings in which:—

Figure 1 is a perspective view of a book, having the end sheets affixed thereto and outspread in position to receive the glue, 55 and this figure also shows the cover ready to be applied to the book; Fig. 2 is a per-

spective view of the completed book; Fig. 3 is a perspective view of a gluing device embodying my invention, shown with the book and end sheets in position therein; 60 Fig. 4 is a plan view of the device with one of the supporting plates removed; Fig. 5 is a front elevation of the same; and Fig. 6 is an inverted sectional plan on the line 6—6 of Fig. 5.

Like numbers refer to like parts in all of the figures.

1 represents a base plate having a fixed bracket 2 extending upward therefrom, on which is detachably mounted a supporting 70 plate 3, said plate extending in a horizontal position. Opposite the fixed bracket 2 and spaced slightly apart therefrom is a second bracket 4 hinged as at 5 to the base plate and provided with a supporting plate 75 3 detachably secured thereto, and similar to the one provided on the fixed bracket. The opposite vertical surfaces 2^a and 4^a of the brackets 2 and 4 being parallel, serve as clamping members between which the book 80 6 is gripped when operated upon. The bracket 4 by virtue of its hinged connection 5 with the base plate is adapted to be tilted away from the fixed bracket 2, to permit the book to be inserted between the two clamping surfaces, and an eccentric lever 7 is pivotally connected to this bracket and engages the base plate, to force this bracket toward the fixed bracket, to clamp the book 85 between said brackets and adjust the plates 90 3 in the same horizontal plane with the back of the book.

The space between the clamping surfaces 2^a and 4^a may be varied by means of the slotted hinged plates 5^a which connect the 95 hinged bracket 4 to the base plate, and by virtue of this adjustment books of various thicknesses may be accommodated in the device.

Plates 3 which support the end sheets in 100 outspread position, being detachable may be removed and replaced by others of a different size to conform to the size and shape of the book cover to be operated upon. A stop 8 extends from the fixed bracket across 105 the rear of the device opposite the space between the clamping surfaces of the brackets and serves as a guide to adjust the position of the book when placed in the device.

The block 9 at the bottom of the space between the brackets may be varied in dimensions to accommodate different sizes of

books and serves as a rest for the lower edge of the book when it is placed in position.

Each of the supporting plates 3 is provided with guides 10 which are used to adjust the cover to proper position when it is placed upon the outspread end sheets.

In using this device, the operator first tilts the hinged bracket 4 away from the fixed bracket 2 and places the book 6 to which the end sheets 11 have been attached, between the clamping surfaces 2^a and 4^a with the said end sheets outspread and supported by the plates 3. In this position the lower edge of the book is supported by the block 9 and the stop 8 is engaged by the rear edge of the book and governs its position in the device. By movement of the eccentric lever 7 the hinged bracket 4 is moved to operative position, clamping the book between the surfaces 2^a and 4^a, and holding the outer surfaces of the end sheets in a horizontal plane flush with the back of the book and in a convenient position to apply glue to the outer surfaces of the end sheets and also to the back of the book. After this has been done, the cover 12 is laid upon the outspread end sheets being located in the proper position by the guides 10 and is then pressed in place which completes the operation, after which the book is released by operation of the eccentric lever 7, which tilts the hinged bracket away from the fixed bracket whereupon the book is readily removed from the device.

What I claim is:

1. A device for attaching book covers, comprising a base, a bracket fixed on the base having a vertical clamping surface and a horizontal supporting surface, a bracket adjustable on the base having a vertical clamping surface opposite the vertical surface of the first bracket and a horizontal surface in the same plane of the horizontal surface of the first bracket, and means for forcing the adjustable bracket toward the fixed bracket.

2. A device for attaching book covers, comprising a base, a bracket fixed on the base having a clamping surface and a supporting surface at right angles thereto, a hinged bracket having a clamping surface and a supporting surface, said clamping surfaces being parallel and spaced apart and the supporting surfaces being in the same plane, and means for forcing said hinged bracket toward the fixed bracket.

3. A device for attaching book covers, comprising a base, a bracket fixed on the base and having a clamping surface, a

bracket hinged to the base and having a clamping surface, said clamping surfaces being parallel and spaced apart, means for varying the space between said clamping surfaces, detachable supporting plates one on each bracket, said plates being in the same plane with each other and at right angles to the clamping surfaces, and means for forcing the hinged bracket toward the fixed bracket.

4. A device for attaching book covers, comprising a base, a bracket fixed on the base and having a clamping surface and a supporting surface at right angles to each other, a hinged bracket having a clamping surface and a supporting surface at right angles to each other, said clamping surfaces being parallel with each other and spaced apart, and the supporting surfaces being in the same plane, means for forcing said hinged bracket toward the fixed bracket, and a stop to be engaged by the rear edge of the book.

5. A device for attaching book covers, comprising a base, a bracket fixed on the base and having a clamping surface and a supporting surface at right angles to each other, a hinged bracket having a clamping surface and a supporting surface at right angles to each other, said clamping surfaces being parallel and spaced apart and the supporting surfaces being in the same plane, means for forcing said hinged bracket toward the fixed bracket, and a removable support for the lower edge of the book.

6. A device for attaching book covers, comprising a base, a bracket fixed on the base and having a clamping surface, a bracket hinged to the base and having a clamping surface, the said clamping surfaces being parallel and spaced apart, and the hinges on the hinged bracket being adjustable to vary the space between the clamping surfaces, a detachable plate on each of said brackets, said plates being in the same plane and at right angles to the clamping surfaces, means for forcing the hinged bracket toward the fixed bracket, a removable support for the lower edge of the book, a stop to be engaged by the rear edge of the book and guides on the supporting plates to govern the location of the cover.

In testimony whereof I affix my signature in presence of two witnesses.

THEODORE S. ETHERIDGE.
